UNITED STATES PATENT OFFICE.

AUGUSTINE R. AYERS AND ROBERT S. MILLER, OF CLEVELAND, OHIO.

RAILWAY FREIGHT-CAR DOOR.

Application filed November 24, 1920. Serial No. 426,126.

To all whom it may concern:

Be it known that we, AUGUSTINE R. AYERS and ROBERT S. MILLER, citizens of the United States, and residents of Cleveland, in the county of Cuyahoga and State of Ohio, have invented certain new and useful Improvements in Railway Freight-Car Doors, of which the following is a specification.

10 Our invention relates to doors for freight cars and more particularly to doors adapted for use upon cars used for shipping automobiles in which the width of the door must necessarily be considerably greater than usual.

15 Our invention more particularly contemplates the provision of stops positioned upon the door guide at the point where the two doors come together.

20 In constructions now generally in use, these stops have been provided by lips on the outside on the back edge of each door which engage a projection of the door posts on the side frame of the car or in some instances, by providing a door post movable with one of the sections and arranged so that when this door is in closed position the door post carried thereby is capable of being locked to castings fastened one on the 25 inside of the side plate and the other on the upper face of the side sill near the middle of the doorway.

30 The other section of the door in these latter constructions locks to the section which carries the movable post.

35 However in a construction designed in accordance with our invention these stops are placed in the door guide ways and positioned centrally so that when each door has 40 abutted the stops it is positioned half way across the door opening and when the doors are subsequently fastened together they are locked securely against movement in either direction.

45 Another distinct advantage in our improved structure resides in the particular positions of the stops. These stops are so placed that when the doors are brought to closed positions and secured together the 50 stop plates are in the case of the lower one, covered by the edge of the door, and in the case of the upper one contained within the inside of the car, to thereby prevent any tampering with the stops and removal of them to permit any unauthorized person 55 gaining entrance to the car. Various minor

features will be made more apparent and the details of our invention more fully illustrated in the accompanying specification and drawings in which:

60 Fig. 1 is a side elevation of a portion of a freight car provided with a door constructed in accordance with our invention,

Fig. 2 is a horizontal section taken on lines 2-2 of Fig. 1,

Fig. 3 is a vertical section taken on lines 3-3 of Fig. 1 looking in the direction of the arrows,

Fig. 4 is the rear elevation showing the stop in position at the upper side of the 70 door frame,

Fig. 5 is a section on lines 5-5 of Fig. 3 looking in the direction of the arrows,

Fig. 6 is a section on lines 6-6 of Fig. 1.

Fig. 7 is a section on lines 7-7 of Fig. 1.

Fig. 8 is an elevation partly in section of a modified form of stop as applied to the lower side of the door frame.

Fig. 9 is a section on lines 9-9 of Fig. 8.

Fig. 10 is a section on lines 10-10 of 80 Fig. 8 and

Fig. 11 is a detailed view of a stop member.

We will first describe the structure illustrated in Figs. 1 to 7 inclusive, in which "C" indicates a freight car of any desired construction provided with a pair of sliding doors D. This pair of doors D are adapted when in closed position to close a doorway of greater width than usual, to 90 thereby enable the car to be used in the shipment of motor vehicles.

The car has the usual frame 10 which carries a suitable track 11 upon which rollers 12 are adapted to travel. These rollers are 95 mounted on hangers 13 of any suitable construction whereby the doors D may be easily moved to open or close the doorway. The lower edge of the doors D is provided with a depending guiding flange 14 which is formed by angularly bent facing plates 15 and 16 secured to the outer and inner faces of the door respectively. The lower frame 10 of the car has secured thereto at separate points angular guiding plates 17 which co-operate 100 with the flange 14 for retaining the lower edge of the door in contact with the car.

105 Posts 18 form the adjacent edges of the doors D and extend throughout the vertical length of the doors. These posts are recessed at their upper ends for the reception of face plates 19. Secured to the under side of the

upper frame 10 is a stop plate 20. A plan of this stop is shown more particularly in Fig. 11. This plate is provided centrally thereof with an abutment 21 formed preferably by bending the plate upon itself as clearly illustrated in Fig. 4. The plate is bent in a horizontal plane so as to offset the abutment from the longitudinal length of the plate 20. Thusly the plate 20 is secured 10 near the edge of the frame 10 and the abutment 21 is properly positioned in the path, or guide way of the upper ends of the doors D. When these doors D are in closed position the facing plates 19 contact the abutment and the wear is taken up by these face plates.

Upon the lower frame 10 of the car is placed a flooring "F" and in order to properly clear this flooring the lower ends of the 20 post 18 are cut away as clearly illustrated in Fig. 3. This cut away portion is faced with an angular facing plate 22. The outside vertical edges of the doors D at the lower ends thereof are faced with angle 25 plates 23. These plates, as illustrated clearly in Figs. 1 and 3, extend over the lower edge of the doors to a point intermediate its height. The lower end of each of these angle plates 23 is positioned between the 30 upstanding sides of the plates 15. Cover plates 24 are then positioned at the lower inside corners of the doors and these cover plates, together with the lower ends of angle plates 23 and of the inside facing plates 22 35 are fastened to the doors by means of bolts 25. Additional bolts 26 are also provided which pass through the extreme lower edges of the doors and secure thereto the lower edge of the cover plates 24 the upstanding 40 side of plate 15 and the lower edges of plates 23 and 22. This construction is most clearly illustrated in Fig. 8.

Secured to the frame 10 of the car and centrally of the door way is a guiding plate 45 27 similarly shaped to the plates 17. The guiding flanges 14 stop adjacent this guiding plate 27 as illustrated at 28 in Fig. 1. This guiding plate 27 is secured to the frame 10 by suitable bolts 29 which pass through the 50 depending side of the angular guiding plate 27 and are secured at the inner side of the frame 10.

The stops for the lower edges of the doors is formed by a pair of angle bars 30, secured 55 to the horizontal portion of the guiding plate 27 by rivets 31 or other suitable securing means. This stop 30 is disposed in the guide way in which the lower edges of the doors travel. The position of these bars 30 60 which form the stop are clearly illustrated in Fig. 5 and in this figure it will be seen that their opposing sides are positioned adjacent one another. The cover plates 24 and the angular facing plates 23 are bent at this 65 point as indicated in Fig. 5 so that when the

doors abut the bottom stop the edges of the door substantially throughout their length will positively abut one another. It will be seen that when the doors are in closed positions the extreme lower ends thereof will 70 stop at 30 and the parts thereof can not be tampered with because they are practically covered by the lower ends of the doors. The wear of the contact with the stop 30 will be taken up by the angle plates 23 and the 75 cover plates 24.

For the purpose of sliding the doors to open and closed positions, suitable handles 80 32 are provided. A standard type of car door locks may be provided such as for instance, illustrated in Fig. 1 and indicated by the numeral 33.

By referring now more particularly to Figs. 8 to 10, inclusive, we will describe the modified form of stop illustrated in these 85 figures. While we have illustrated this stop as positioned at the bottom of the frame, it will be apparent that we may employ this type of stop equally as well at the top of the doorway. The bottom frame 10 of the car has supported thereon the stop which is formed with a web 34 which extends substantially the whole outside face of the frame or side sills of the car over the top thereof and downwardly a short distance on the inner side thereof, as illustrated clearly in Fig. 9. Suitable bolts 35 extend through from the outer side thereof and are secured in position by nuts 36 at the inner side of the frame 10. The floor F is then placed over the top of the 90 web which is disposed on the top side of the frame or sill 10. A stop or abutment 37 as shown is cast integrally as are also the vertically disposed reinforcing ribs 38. The accompanying parts remain unchanged from that described and illustrated in Figs. 1 to 7.

A stop constructed in accordance with the modification is more particularly in the nature of a burglar-proof construction, inasmuch as the flooring F would have to be removed before the web 34 and stop 37 could be taken off and the flooring F could not be removed until access had been gained to the interior of the car.

The advantage of a structure similar to 115 either of the two hereinbefore described is obvious inasmuch as that when the stops are arranged centrally of the doorway, the doors may be rapidly closed and will properly be positioned for locking with respect to the doorway when they contact with the abutments or stops. When the doors are thereupon locked and sealed as is usual with freight car doors, they cannot thereafter be opened by unauthorized persons, inasmuch 120 as the centrally disposed abutments prevent movement of the doors in either direction. Furthermore, when the doors are closed the stops or abutments are so covered or concealed by the doors as to make it extremely 125 130

difficult for any one to remove the stops and enable them to slide the doors from the doorway and gain access to the car.

We do not wish to be limited in any respect to the particular structures illustrated, inasmuch as various changes and modifications may be resorted to in carrying out our invention without departing from the spirit and scope thereof, and we particularly serve this right.

Having thus described our invention what we claim is:

1. A freight car door construction comprising a pair of sliding doors adapted to close a doorway, posts positioned at the opposing edges of said doors, guide ways for said doors, said posts being recessed at their ends for the reception of face plates, stops positioned centrally of the doorway for limiting the movement of said doors, one of said stops comprising a plate secured to the frame of the doorway and bent upon itself to form an abutment which projects into the path of said doorway and is engaged by the corresponding face plates, the other of said stops embodying an angular guiding plate secured to the doorway frame and a pair of angle plates secured thereto and projecting into the path of said doors to be engaged by the corresponding face plates, said stops being so positioned that when the doors are in closed position they are covered thereby.

2. A freight car door construction which comprises a pair of sliding doors adapted

to close a doorway, posts positioned at the opposing edges of said doors, facing plates carried by said posts on their opposing sides, said posts being recessed for the reception of said facing plates, stops disposed centrally of the doorway for limiting the movement of said doors, said posts being suitably cut away and said facing plates bent to accommodate said stops, one of said stops comprising a plate secured to the frame of the doorway, bent upon itself to form an abutment and bent so as to offset the abutment from the longitudinal length of the plate.

3. A freight car door construction comprising a pair of sliding doors adapted to close the doorway and arranged on the outside face of said car and a fixed combined stop and guide secured to said car adjacent the bottom edge of said doors whereby said doors may be guided to prevent lateral displacement and the movement of said doors arrested in the closed position and means for locking said doors.

4. A freight car door construction which comprises sliding doors, a doorway frame, facing plates on the opposite edges of said doors, stops arranged in the guide-ways of said doors, one of said stops comprising a pair of angle plates, an angle guiding plate, carrying said stop and positioning it to be abutted by the lower ends of the doors.

AUGUSTINE R. AYERS.
ROBERT S. MILLER.
